UNITED STATES PATENT OFFICE.

HARADEN PRATT, OF SAN FRANCISCO, HAROLD F. ELLIOTT, OF PALO ALTO, AND EUGENE B. MURPHY, OF BURLINGAME, CALIFORNIA, ASSIGNORS TO AUGUSTUS TAYLOR, OF SAN FRANCISCO, CALIFORNIA.

RADIOTELEGRAPH SIGNALING SYSTEM.

Application filed January 3, 1921. Serial No. 434,420.

To all whom it may concern:

Be it known that we, HARADEN PRATT, HAROLD F. ELLIOTT, and EUGENE B. MURPHY, citizens of the United States, residing, respectively, in the city and county of San Francisco, Palo Alto, Santa Clara County, and Burlingame, San Mateo County, all in the State of California, have invented certain new and useful Radiotelegraph Signaling Systems, of which the following is a specification.

The invention relates to a radio telegraph signaling system in which audio frequency wave trains are radiated from an antenna system to which an undamped wave arc generator is connected.

It is desirable for several reasons, under certain conditions, to produce audio frequency wave trains from a continuous undamped wave transmission system and several methods have been suggested for accomplishing such result. In these methods the continuous wave has been broken up into time spaced groups at such a frequency that the group frequency is within the range of audibility. This has been accomplished by interrupting the antenna circuit at an audio frequency rate and shunting the arc with a condenser circuit or an oscillatory circuit, into which the radio frequency current passed during the interval that the antenna circuit was opened, or during the time that its resistance was largely increased. These methods all involve the continuous and normal operation of the arc, and during the intervals of no radiation the energy of the arc is wasted in the shunt or oscillatory circuit.

An object of our invention is to produce modulation of the antenna current at audio frequencies, in an arc radio transmitter.

Another object of our invention is to eliminate a certain waste of energy in performing such modulation for producing a more economically operating system.

The invention possesses other advantageous features, some of which, with the foregoing, will be set forth at length in the following description, where we shall outline in full the method of our invention and several forms of systems for putting it into practice, which systems are shown in the drawings accompanying and forming part

of the present specification. In said drawings, we have shown several systems for carrying out our invention, but it is to be understood that we do not limit ourselves to such systems, since the method, as expressed in the claims, may be embodied in other systems.

Referring to such drawings:

Figures 1 to 11 inclusive, are diagrammatic representations of different forms of the system of our invention.

In accordance with our invention, we provide for the audio frequency modulation of an arc generated radio frequency current, by extinguishing and reigniting the arc flame at an audio frequency rate, by suitable means such as an oscillatory circuit resistance control. By extinguishing and reigniting the arc at audio frequency, groups of undamped waves are radiated from the antenna, the groups being emitted at audio frequency. During the time that the arc is extinguished, there is very little energy consumption, so that a gain in efficiency of operation is obtained.

We have found that it is a fundamental characteristic of the arc, that is, the Poulsen arc, when used as a converter of energy for producing radio frequency currents, that the arc length must increase when the resistance of the oscillatory circuit is increased, if oscillations are to be maintained. In order to maintain a longer arc, it is necessary to supply a higher direct current voltage, and, if this is not done, the arc is immediately extinguished, due to the action of the transverse magnetic field. The voltage of the direct current generator being maintained substantially constant, when the resistance of the oscillatory circuit is increased, the arc is instantaneously extinguished.

We have further found that if the oscillatory circuit resistance is inserted and then quickly withdrawn, the extinguished arc will immediately reignite, due to the presence of conducting ions in the arc path produced by the incandescent electrode, or electrodes, which have not cooled appreciably during the interval of interruption. Experiments have shown that a resistance of sufficient value to extinguish the arc may be inserted into and removed from the an-

tenna circuit at an audio frequency rate, with extinction and ignition of the arc flame at the same rate, producing an antenna current with corresponding amplitude fluctuations, producing thus suitable wave trains. In accordance with our invention, we increase and decrease the resistance of the antenna circuit at audio frequency, thereby interrupting and reigniting the arc at such frequency and produce audio frequency wave groups in the antenna circuit.

In the drawings we have shown several different circuits embodying the system of our invention. Each circuit includes a Poulsen arc generator, comprising an arc 2 enclosed in an atmosphere containing hydrogen, and subjected to a strong transverse magnetic field produced by the electromagnets 3, which are energized by direct current from the generator 4. One side of the arc is grounded and the other side is connected to the antenna 5, through the variable inductance 6. Means are provided for introducing into and withdrawing from the antenna circuit, at audio frequency, resistance sufficient to extinguish the arc when introduced into the circuit. In the system shown in Fig. 1, the resistance 7 is arranged in the antenna circuit and shunted around the resistance is a low resistance circuit containing a rotary, motor driven commutator 8, having alternate insulating segments and commutator segments. The commutator is engaged by brushes having a suitable width. The rotating commutator periodically short-circuits the resistance 7, so that the resistance is alternately effectively placed into and removed from the circuit. The commutator is rotated at such speed that the arc is interrupted at audio frequency.

In the system shown in Fig. 2, the resistance 9 is arranged in the commutator circuit which is arranged in parallel with a portion of the oscillatory circuit inductance 6 which is equivalent to introducing the resistance directly in series in the oscillatory circuit.

The system shown in Fig. 3 is similar to that shown in Fig. 2, with the exception that the commutator-resistance circuit is coupled to the oscillatory circuit by an air-core transformer 12. In the system shown in Fig. 4, an iron core transformer 13 is employed in place of the air core transformer.

The system shown in Fig. 5 is similar to that shown in Fig. 2, with the exception that the commutator circuit is connected around a condenser 14, instead of around a portion of the inductance 6.

The systems shown in Figs. 6, 7, 8 and 9 are modifications of the systems shown in Figs. 2, 3, 4 and 5 respectively, in which a rotary spark gap device 15 is substituted for the commutator 8. When the spark gap electrodes come into alignment, the potential in the circuit causes a spark discharge there-

by closing the circuit through the resistance, which has the equivalent effect of inserting the resistance in the oscillatory circuit.

In Fig. 10, we have shown a system showing the application of this method of signaling to coupled circuits. The arc 2 is contained in a closed circuit containing the capacity 25 and the transformer primary 26, which is coupled to the secondary 27 in the antenna circuit. The interrupter 28 is associated with the circuit to which the arc converter is connected in the present instance, the interrupter being arranged to shunt a resistance 29 in the circuit.

The circuits shown in Figs. 4 and 8, involving the use of the iron core transformer coupling, will only work properly when there are few losses in the iron core, which condition it is often difficult to realize in practice. The system shown in Fig. 11 will give satisfactory operation with an iron core transformer having substantial losses. In this system the resistance 31 is permanently connected across the secondary of the iron core transformer 32 and the interrupter 33 is connected across the resistance, so that it operates to short circuit the resistance.

It is to be understood that in the above circuits the rotary commutators and spark gaps are so designed as to cause connections or sparks to be made at any convenient audio frequency rate. The times of contact making or sparking which are determined by the relative widths of the metallic and insulated commutator segments, or by the relative widths of the electrodes and spaces on the rotary gap disc, constitute a feature of this invention as best results are obtained when a definite ratio in these times is selected.

It is to be further understood that the resistances and transformer ratios are so selected in each of the above examples that the equivalent resistances, respectively, of the oscillatory circuits, will be as great or greater than the amount required for complete arc extinguishment. These quantities may be easily determined by calculation, or by trial.

The circuit constants are further so arranged that a low voltage is utilized with the commutator connection so that sparking at the brushes of the latter may be a minimum, and a high voltage with the spark gap so that the discharges across the latter may be uniform and regular.

Signaling may be accomplished in any suitable manner, and in the drawings we have shown one form of signaling circuit which is particularly applicable to the system of this invention. Connected around the arc is a circuit 16 containing a resistance 17 and a normally closed relay key 18. The relay key is operated by the electromagnet 19 arranged in the circuit of the battery 21

and the normally closed signaling key 22. When the circuit 16 is open, radio frequency current is delivered to the antenna and when the circuit 16 is closed, the resistance 17
5 short-circuits the arc, thereby extinguishing it entirely. The contacts of the relay key 18 may be placed within the arc chamber in a position which causes the spark produced by their opening, to reignite the arc
10 flame, which feature has been set forth in application Serial No. 368,193, filed in the Patent Office on March 23, 1920 by Harold F. Elliott and patented September 14, 1920, No. 1,352,883.

15 We claim:

1. The method of transmitting radio signals by the aid of an arc converter and a transmission circuit in such a way that audio frequency groups may be sent, which comprises inserting in the circuit and withdrawing from the circuit at an audio frequency rate, an energy consuming device, whereby the arc is extinguished and reignited at this rate.
- 25 2. The method of producing in an oscillatory circuit, current groups having an audio group frequency, with an arc suitable for generating sustained alternating currents, which comprises introducing and
30 withdrawing resistance from said circuit at an audio frequency rate, the value of the

resistance being such that when introduced in the circuit, the arc is extinguished.

3. A radio telegraph signaling system comprising an arc, an oscillatory circuit connected to the arc, a resistance of such value that when introduced into the circuit the arc is extinguished, and means for introducing the resistance into the circuit and withdrawing it therefrom at an audio frequency rate. 35

4. A radio telegraph signaling system, comprising an arc, an oscillatory circuit connected to the arc, a resistance of such value that when introduced into the circuit the arc is extinguished and a rotary make and break 45 device adapted to introduce the resistance into the circuit and withdraw it therefrom at an audio frequency rate.

5. A radio telegraph transmission system, comprising an arc converter, a transmission 50 circuit connected to the arc, and means for alternately extinguishing and reigniting the arc at an audio frequency, comprising an energy absorbing device, and means for connecting in and disconnecting said device 55 from the circuit at an audio frequency rate.

In testimony whereof, we have hereunto set our hands.

HARADEN PRATT.
